UNITED STATES PATENT OFFICE.

THOMAS SINGLETON, JR., OF NEW BEDFORD, MASSACHUSETTS, ASSIGNOR
TO THE MOUNT WASHINGTON GLASS COMPANY, OF SAME PLACE.

DESIGN FOR AN ORNAMENTAL GLASS DISH.

SPECIFICATION forming part of Design No. 22,170, dated January 31, 1893.

Application filed September 22, 1892. Serial No. 446,842. Term of patent 7 years.

To all whom it may concern:

Be it known that I, THOMAS SINGLETON, Jr., of New Bedford, in the county of Bristol and State of Massachusetts, have invented and produced a new and original Design for Glassware, of which the following is a specification, reference being had to the accompanying drawings, illustrating the same, embodied in a bowl or shallow dish.

10 Figure 1 is a plan view and Fig. 2 a sectional view of a bowl or dish containing my design.

The leading feature of my design consists of a series of rectangular fields formed by a 15 series of parallel indentations extending across the bottom of the dish crossed by another series of parallel indentations across the bottom of the dish, the second series of indentations being at right angles essentially to the first 20 series; these fields being filled, in whole or in part, by ornamental figures; the bottom of the dish being made many sided and the edge formed by corresponding projections.

a a' &c. are parallel indentations across the bottom of the dish and *b b' &c.* are a series of 25 parallel indentations across the bottom of the dish, the indentations *b b' &c.* being substantially at right angles to the series of indentations *a a' &c.* By these indentations the dish is divided into fields, which may be variously 30 ornamented, the ornamentation extending from one field into another if desired as shown. The side of the dish is formed by a conventionalized rose A, the rose like figures A alternating with the kite shaped figures F form 35 the margin of the bottom.

Dishes containing my design may be made of cut or pressed glass, or otherwise, if desired.

What I claim is:

The design for an ornamented glass dish, as 40 herein shown and described.

THOMAS SINGLETON, JR.
